INVENTOR.
WALTER OLSEN,
BY HIS ATTORNEY
James F. Williamson.

UNITED STATES PATENT OFFICE.

WALTER OLSEN, OF ALBERT LEA, MINNESOTA, ASSIGNOR TO AMERICAN GAS MACHINE CO., OF ALBERT LEA, MINNESOTA, A CORPORATION OF MINNESOTA.

COLLAPSIBLE OVEN AND CARRYING CASE.

1,404,314.

Specification of Letters Patent. Patented Jan. 24, 1922.

Application filed March 10, 1921. Serial No. 451,165.

To all whom it may concern:

Be it known that I, WALTER OLSEN, a citizen of the United States, residing at Albert Lea, in the county of Freeborn and State of Minnesota, have invented certain new and useful Improvements in Collapsible Ovens and Carrying Cases; and I do hereby declare the following to be a full, clear, and exact description of the invention, such as will enable others skilled in the art to which it appertains to make and use the same.

This invention relates to a device which is designed to be used as an oven to be placed on a small stove such as is often used in camping outfits. The device is also constructed so that it may be collapsed into a small space and when so collapsed can be used as a carrying cabinet, in which a small stove or any other desired articles may be packed and carried.

It is an object of this invention to provide such a device having a small number of parts, which parts are designed to be folded into a very small space.

25 This and other objects and advantages of the invention will become apparent from the following description made in connection with the accompanying drawings in which like reference characters refer to the same parts throughout the different views and in which—

Fig. 1 is a central longitudinal section of the device showing the same arranged as an oven;

35 Fig. 2 is a transverse central section thereof;

Fig. 3 is a transverse central section of the device showing the same collapsed for use as a carrying case; and

40 Fig. 4 is a longitudinal central section of the cover or lid for the device.

Referring to the drawings:

The device comprises a member 1 which is formed as a rectangular box open at its upper end. This member is preferably made of thin sheet metal and the exposed edges thereof will be suitably relieved of sharp portions. As stated, the device is open at its upper end and has an opening 2 cut in its bottom portion leaving the outstanding flange 3 surrounding said opening. A frame member designated generally as α is arranged to co-operate and be supported by the member 1. The member α comprises 55 a grid formed with longitudinal spaced rod

members 4 which are connected at their end portions by transverse rod members 5 shown as disposed thereabove. A flat piece of metal 6 has its lower edge bent around the outer rod 4 and is formed at its upper edge with an outturned U-bend which as shown in Fig. 2 is adapted to engage with the upper side edge of the member 1. The outer edge of the member 6 is again turned upwardly a short distance to form a longitudinally extending trough 6^a which will be disposed outside of the member 1. It will be understood that there is a member 6 at each side of the frame member α . Rod members 7 have their upper ends formed as rings or loops and enclosing certain of the rods 4, which as shown in Fig. 2 are the ones adjacent to the outermost rods. The rods 7 have their intermediate portions depending and extending longitudinally under the said rods 4 and a plate member 8 has its side edges bent around the member 7 and is supported by and extends between the same, being thus supported at some distance below the grid member.

80 The casing member 9 which also comprises a rectangular box member having one side open is provided to form the top or cover for the member 1. Member 9 is also preferably formed of thin sheet metal and will also preferably have its exposed edges suitably relieved of sharp portions. The dimensions of the member 9 are such that it can be placed over the member 1 as shown in Fig. 2 and its side edges will rest in the trough member 6^a while its end edges will extend along outside of the end edges of member 1 as shown in Fig. 1. The member 1 is provided at one side substantially centrally thereof with a handle 10 which is of general rectangular shape having its end portion turned outwardly and secured in small U-shaped bearing clips 11, which project on the inside of the member 9 and have their inner edges bent outwardly on the inside thereof. Member 9 is also provided at its ends near the edge portion thereof with centrally disposed projecting pins 12 for a purpose to be later described.

100 From the structure so far described, it will be apparent that the frame member α will be collapsed into substantially the form shown in Fig. 3. When the members 7 are folded downwardly onto the plate 8 and the members 6 are likewise folded downwardly 110

into contact with the rods 4, the frame *a* as so folded is disposed in the bottom of member 1 and said member is then placed in the member 9.

5 A convenient member 13 is provided which is also formed as a shallow rectangular box having an open side and said member has pivoted on its inside surface a plate 14 which is provided with spaced apertures 15 near 10 one edge through which extend small curved bearing clips 16 which have an extended portion, which is riveted or otherwise suitably secured to the top of the member 13. The member 13 is provided centrally of its 15 end portions near the open edge thereof with apertures 14^a. It will, of course, be understood that the exposed edges of the members 13 and 14 can be suitably beaded or inturned so that the same will not be 20 objectionably sharp or rough.

When the device is disposed as shown in Figs. 1 and 2, it forms a simple and convenient oven or cooking chamber adapted for use with a small stove of any type, 25 or the same can be placed between stones or brackets over a fire. The pans or cooking receptacles will be placed on the grid formed by members 4 and 5 and the plate 8 will constitute a heat deflecting or radiating plate. 30 When the device is so used as an oven, the member 14 can be swung open in respect to the lid 13 and these members can then be placed about the stove or fire to form a suitable wind shield therefor. It will thus be 35 seen that the device forms a compact, simple and efficient oven or cooking chamber.

When it is desired to transport the device, the same will be collapsed as shown in Fig. 3 with the casing 1 disposed in the member 40 9. The lid 13 will then be placed on the member 9 as shown in said figure and the holes 14^a in the lid will engage over the pins 12, this engagement being made possible by the resiliency of the metal. To engage or 45 disengage the pins 12, the ends of the member 9 are pressed slightly inwardly and when relieved will spring out and when the pins are thus located in the apertures 14^a there will be no tendency for the same to 50 be disengaged. With the lid in position, the device is now converted into a rectangular carrying case, which can be lifted and carried by the handle 10. The device is designed particularly to conveniently receive 55 and carry the collapsed camp stove described and claimed in the pending application S. N. 181,938, filed July 21, 1917, by Hans C. Hanson. It will, of course, be obvious that any desired articles may be placed in the carrying case and transported.

60 From the above description it will be seen that applicant has produced a simple and efficient device and one which will have great utility for the purpose intended. The 65 same can be cheaply made. The parts of the

device are so constructed that there is nothing to become disarranged or get out of order and can be quickly set up as an oven or disassembled as a carrying case. In practice, the casing parts 1, 9, 13 and 14 will preferably be painted or coated with suitable non-corrosive material. 70

It will, of course, be understood that various changes may be made in the form, details and proportions of the parts without departing from the scope of applicant's invention, which generally stated consists in the matter shown and described and set forth in the appended claims. 75

What is claimed is: 80

1. A combined oven and carrying case comprising an open ended box-like casing having an aperture in the bottom thereof, a collapsible grid, supporting means adapted to be disposed in and supported by said 85 casing, and a cover member having an open side adapted to be supported by said casing, said box-like member being adapted to be telescoped into the cover member.

2. A combined oven and carrying case 90 having in combination a box-like casing having one side open and a large aperture in its other side, a grid member, means pivoted to said grid and adapted to engage the side edges of said casing and to form supporting means at the outside thereof, a deflecting plate pivotally connected to said grid and suspended below the same, and a cover casing comprising a box-like member having an open side adapted to be disposed over the 100 first mentioned casing with its side edges engaging the said supporting means, said grid, supporting means, and deflecting plate being constructed and arranged to be folded into a comparatively small space in the bottom of the first mentioned casing and the first mentioned casing being adapted to telescope into the second mentioned casing. 105

3. A combined oven and carrying case having in combination a box-like casing having an open side and a large opening through its other side, a collapsible grid and support, a cover member comprising a box-like casing having an open side adapted to be supported on said grid support, said grid member being constructed and arranged to be folded into a small space in the first mentioned casing and the first mentioned casing being adapted to telescope into the said cover member, and a lid member adapted to fit over the open side of the second mentioned casing and be secured thereto. 110 115

4. In a combined oven and carrying case structure having a cover member forming the body of the carrying case, a lid adapted to fit over and close said cover member, a hinged plate pivoted to the inside of said lid member, said lid and plate being adapted to be opened out and used as a wind shield when the device is used as an oven. 120 125 130

5. The structure set forth in claim 3 and a handle secured to the second mentioned casing by which the same can be carried.

6. In an oven comprising a box-like casing having an open upper side, a grid means comprising a grid member, supporting plates pivoted at the sides of said grid and having their upper ends bent to extend over the side portions of the casing and having their outer edges upturned to form a cover supporting means.

7. The structure set forth in claim 6 and a heat deflecting plate suspended below said grid member and having supporting means pivoted thereto and to said grid member.

8. A combined oven and carrying case comprising two box-like casings, the one adapted to telescope into the other, a collapsible grid and heat deflecting member adapt-

ed to be received in the smaller of said casings and a cover member for the larger casing.

9. The structure set forth in claim 8 and catch means for securing said cover and larger casing together.

10. A device of the class described comprising a substantially rectangular casing having one open side and an opening in its opposite side, a second substantially rectangular casing having an open side into which said first mentioned casing is adapted to telescope, and a collapsible member adapted to be supported in said first mentioned casing and constituting a grid member, and a support for said second mentioned casing.

In testimony whereof I affix my signature.

WALTER OLSEN.
